United States Patent Office

Des. 175,345
Patented Aug. 16, 1955

175,345

VACUUM CLEANER OR SIMILAR ARTICLE

Lurelle V. A. Guild, Noroton Heights, Robert C. Lampe, Stamford, and George W. Norrick, New Canaan, Conn., assignors to Electrolux Corporation, Old Greenwich, Conn., a corporation of Delaware

Application November 23, 1954, Serial No. 33,208

Term of patent 14 years

(Cl. D9—2)

FIG. 3

FIG. 4

FIG. 5

Fig. 1 is a perspective view showing the side, top and front of a vacuum cleaner embodying our new design;

Fig. 2 is a side view of the vacuum cleaner shown in Fig. 1;

Fig. 3 is a front view of the vacuum cleaner shown in Figs. 1 and 2; and

Fig. 4 is a rear view of the vacuum cleaner shown in the preceding figures.

Fig. 5, a top plan view of the invention.

The side of the vacuum cleaner not shown in the drawings is the same as the side illustrated in Fig. 2.

We claim:

The ornamental design for a vacuum cleaner or similar article, as shown and described.
